(57) **CLAIM**

The ornamental design for a door threshold, as shown and described.

DESCRIPTION

FIG. 1 is a front perspective view of a door threshold. FIG. 2 is a front elevational view of a door threshold. FIG. 3 is a rear elevational view of a door threshold. FIG. 4 is a right side elevational view of a door threshold. FIG. 5 is a left side elevational view of a door threshold. FIG. 6 is a top plan view of a door threshold. FIG. 7 is a bottom plan view of a door threshold; and, FIG. 8 is a front perspective view of a door threshold. The broken lines shown in FIG. 6 illustrate portions of the door threshold that form no part of the claimed design.

1 Claim, 5 Drawing Sheets
